Inventor:
George S. Leddick,
by *George S. Leddick*,
His Attorney.

UNITED STATES PATENT OFFICE.

GEORGE S. LEDDICK, OF SCHENECTADY, NEW YORK, ASSIGNOR TO GENERAL ELECTRIC COMPANY, A CORPORATION OF NEW YORK.

SWITCH ASSEMBLY.

Application filed July 13, 1925. Serial No. 43,209.

To all whom it may concern:

Be it known that I, GEORGE S. LEDDICK, a citizen of the United States, residing in the city of Schenectady, county of Schenectady, 5 State of New York, have invented certain new and useful Improvements in Switch Assemblies, of which the following is a specification.

My invention relates to improvements in 10 electric switches and in particular to details of construction and arrangement whereby the switch assembly is compact and convenient, and nevertheless such that the labor necessary for assembly is not excessive.

15 Although not necessarily limited thereto, the invention is particularly applicable to switch assemblies such as motor starting compensators which comprise an auto-transformer, switch mechanism or contactors for 20 establishing the motor connections, and devices such as relays and the like for controlling the switch mechanism.

One of the features of the invention is the 25 provision of a contactor panel pivotally mounted within a casing, the panel having contactors thereon mounted back to back on opposite sides of the panel, the contactor or contactors on one side of the panel facing the front opening of the casing and the contactor or contactors on the other side of the panel facing 30 the rear conduit outlet opening of the casing, whereby by tilting the panel toward the front opening the contactor or contactors on the rear side of the panel are 35 readily accessible for inspection.

Other features of the invention will be 40 pointed out particularly as the specification proceeds, and reference is had to the accompanying drawings showing an embodiment 45 of the invention, Fig. 1 of which is a perspective view of the switch assembly with a portion of the casing removed for the purpose of explaining the features of construction and arrangement, Fig. 2 is a detail for 50 the purpose of showing the mechanical interlocking arrangement between the contactors on opposite sides of the contactor panel, and Fig. 3 is a side view of the arrangement of Fig. 1 with the end portion 55 of the casing removed.

Referring to the drawings, the switch assembly is enclosed within a casing 10 which is provided with a rear opening which 60 operates with the conduit outlet box 11 so 65 as to form a completely enclosed receptacle

for the switch assembly and the conductors leading therefrom. The panel 12, of any suitable insulating material, is pivotally mounted within the casing, the lower edge of the panel being provided at each end 60 thereof with a forked supporting member 13 which forms an open pivotal bearing for the panel on the supporting rod 14 which extends transversely of the casing. This supporting rod is secured in the side walls 65 of the casing, and the arrangement is such that by reason of the open pivotal bearing of the contactor panel, this panel may be very readily assembled within the casing and also be very readily removed for the 70 purpose of inspection and repair. The contactor panel has a three pole electromagnetic switch or contactor 15 mounted on the rear of the panel, facing the rear conduit outlet opening, and another contactor 16 on the 75 front of the panel, facing the front opening of the casing. These contactors are mounted back to back on opposite sides of the panel, thereby making the most effective use of the contactor panel and minimizing very great- 80 ly the total space taken up by the panel and the contactors.

These contactors are of any suitable construction, and I have shown a well known type of contactor employing each an operating rod 17 carrying a plurality of movable contacts (not shown) which cooperate with in the arc chutes 18 with corresponding stationary contacts. The operating rods are each operated by means of a separate armature 19 of an electromagnetic operating means having a winding 20 on the magnetic structure thereof. It is believed that a detailed description of this particular type of electromagnetic switch or contactor is un- 95 necessary to an understanding of the invention, since the type which I have shown is a well known form and, furthermore, the invention is not necessarily limited to any particular type of electromagnetic switch or 100 contactor. The contactors are interlocked so as to prevent the one contactor from closing while the other contactor is closed, and this feature of the invention is illustrated clearly in Fig. 2, in which the mechanical 105 interlock 21 cooperates with the operating shafts 17 of the two contactors so as to permit either contactor to close, provided the other contactor is open, but which prevents the closing of either contactor provided the 110

other contactor is closed. This mechanical interlock extends through the panel as shown, thereby also economizing in the space taken by this part of the mechanism.

5 The contactor panel is normally in the position indicated in Fig. 3, in which the panel is held in the vertical position by means of the catches 22 which cooperate with the cross rod 23 having its end secured in 10 the side walls of the casing 10. It will be observed that in Fig. 3 the contactor 16 is shown in the attracted or closed position and the contactor 15 is shown in the open or unattracted position. As applied to a starting 15 compensator, the contactor 16 may be employed as the starting switch for connecting a motor to a source of supply (not shown) through the reduced voltage taps of the auto-transformer 24. The contactor 15 will 20 then be employed to connect the motor directly to the source of supply after the motor has started on the reduced voltage tap of the auto-transformer. A system of motor control employing the auto-transformer, the 25 switch mechanism and the relays employed in the switch assembly of my invention, has not been shown for the reason that such systems of motor control are old and well understood by those skilled in the art, and for 30 the further reason that the motor control system is not of the essence of my invention. It will be understood in reading the drawings that in Fig. 3 the switch mechanism is in such a position that the motor starting 35 connections have been established, and that in the normal position of the contactors, the contactor 16 will be in its biased or open position, the same as the contactor 15. When the contactors 16 and 15 are in their respective open positions, the controlled motor 40 (not shown) will be disconnected from the source of supply (not shown).

The front of the casing 10 is provided with a pivotally mounted cover or door 25, which 45 is held in the closed position in any suitable manner. I have indicated the locking mechanism 26 for this purpose, but the invention is not limited to any particular type of locking mechanism. It will be observed that the 50 contactor 16 is readily accessible from the front or top of the casing by opening the door 25, but that the contactor 15 in the rear of the panel 12 is not accessible with the contactor panel in its vertical position as 55 shown in Fig. 3. However, by reason of the fact that the contactor panel is pivotally mounted within the casing, the contactor 15 in the rear of the panel may be readily inspected from the front or the top of the 60 casing by backing off the catches 22 and releasing these catches from the rod 23, thus permitting the panel 12 to be tilted toward the front of the casing. The contactor panel is shown in this position in Fig. 1, and it will 65 be observed that the catch 27 is provided for

engaging the rod 23 and thereby securely holding this panel in the proper position within the casing for the inspection of the rear contactor 15 from the front of the casing.

It will also be noted that the terminal board 28 is secured on the rear wall of the casing 10 adjacent the conduit outlet opening of the casing, thereby forming a very convenient assembly of the apparatus and 70 further providing that this terminal board is normally hidden from view so as to prevent tampering with the same by unauthorized persons. Since the connections to this terminal board are ordinarily left as originally 75 made, it is desirable that this terminal board be out of view ordinarily, but nevertheless be readily accessible to authorized persons in case it is desired to remove the connections. It can readily be seen that the terminal 80 board is readily accessible from the front or top of the casing when the contactor panel is tilted toward the front of the casing as shown in Fig. 1. One of the advantages of 85 the construction and arrangement is that the conduit outlet box 11 may be installed, the cables 29 brought in and permanently connected to the terminal board 28 before the rest of the switch mechanism is installed. This is advantageous since the electricians 90 wiring a building are able to finish their 95 wiring completely to the compensator, so that the compensator may be installed at any later time.

The enclosing case is supported in position 100 by means of the conduit outlet box 11 which is secured in any suitable manner to a frame work or the walls of a building or the like, and also by means of the supporting straps 30 which are secured to the lower end of the casing. The auto-transformer 24 is secured within the casing to the rear wall thereof and beneath and to the rear of the contactor 105 panel 12. This auto-transformer is secured to the casing in any suitable manner and I 110 have indicated the straps 31 for this purpose. The auto-transformer is also supported by the bracket 31^a and the bracket 31^b supports the auto-transformer in case the straps 31 115 become loosened and the casing is turned upside down during shipment. The auto-transformer is a part of the apparatus which 120 ordinarily needs no inspection during the ordinary life of the compensator, so that this arrangement of the parts places the auto-transformer in such a position that it is quite unlikely that an operator would ever come in engagement therewith. The starting and running contactors are controlled by means 125 of relays which are mounted on the support 32, which has its ends secured to the side walls of the casing 10 and is secured in position within the casing beneath and to the front of the contactor panel 12. This support provides a stiffening member for the 130

casing as well as a support for the thermal protective relay 33 and the time element relay 34.

In general it may be said that the relay 33 may be of any suitable type for the protection of the motor against overheating. I have shown the relay as of the type disclosed and claimed in the patent to Chester I. Hall, No. 1,527,645, dated February 24, 1925. This thermal relay is provided with a reset mechanism to which the pull cord 35 is attached so that when the relay operates to open the motor controlling contactors in response to an overload in the usual manner, the relay may be reset without opening the casing by merely pulling on the cord 35. The time element relay 34 is provided for introducing a definite time interval between the closing of the starting contactor 16 and the closing of the running contactor 15. My invention is not limited to any specific form of time element relay, and I have shown somewhat in outline the time element relay fully disclosed and claimed in the patent to Chester I. Hall, No. 1,483,433, dated February 12, 1924. This relay is provided with an enclosing cover 36 to protect the various parts of the relay from dust and from injury due to other causes. This relay is capable of adjustment over a rather large range, as is set forth in the said Chester I. Hall patent, and after the relay has been set for the particular installation, the setting thereof will ordinarily not need to be changed as long as the controlled motor is performing the same work. However, it will be observed that in case it is desired to adjust either the thermal protective relay 33 or the time element relay 34, this may be readily done without disturbing any of the apparatus within the casing after the front door 25 of the casing has been opened. It will be apparent from the foregoing that my switch assembly makes possible the enclosure of a comparatively large amount of apparatus by means of a relatively small enclosing casing, since the space within the casing is used to the greatest advantage. Furthermore, it will be seen that all of the parts of the apparatus which ordinarily ever need inspection are readily accessible for that purpose. The starting contactor 16, the controlling relays 33 and 34 are readily accessible, and the running contactor 15 on the rear of the panel and the terminal board 28 adjacent the rear conduit outlet opening are readily accessible by merely tilting the panel about its pivotal support within the casing. It will also be observed that the arrangement has features of advantage from the standpoint of assembly. In other words, the contactor panel may be assembled as a unit with the proper electrical conductors leading therefrom, and this panel may be very readily assembled within the casing

by mounting the panel on the supporting rod 14. With the panel tilted forward as shown in Fig. 1, the connections to the rear terminal board may be very readily and conveniently made. It will also be observed that the contactor panel may be very readily removed from the casing for repairs by simply tilting the panel to the position as shown in Fig. 1, removing the connections between the panel and the terminal board and lifting the panel out of the casing. This is of advantage, since the contactors are the parts of the assembly which get the most severe service and which ordinarily need most frequent inspection and repair. The top cover of the casing is readily removed by loosening the catch and unhooking this cover from the pins 37, thus permitting of ready inspection of the switch assembly from the top of the casing.

What I claim as new and desire to secure by Letters Patent of the United States, is:

1. A switch assembly comprising a casing, a contactor panel mounted within said casing and having a pivotal bearing with respect thereto, the said panel having two electromagnetic switches mounted back to back on opposite sides of said panel.

2. A switch assembly comprising a casing, a contactor panel mounted within said casing and having an open pivotal bearing with respect thereto, the said panel having two contactors mounted back to back on opposite sides of said panel, whereby the contactors and panel take up a minimum of the space within the casing, the panel with the contactors thereon is readily assembled within the casing and readily removed therefrom, and the contactors may be readily inspected by tilting the panel about its support.

3. A switch assembly comprising a casing, a contactor panel pivotally mounted within said casing, the said panel having two contactors mounted back to back on opposite sides of said panel, and a mechanical interlock extending through the panel and cooperating with said contactors for maintaining one of the contactors open while the other is closed.

4. A switch assembly comprising a pivotally mounted support, an electromagnetic switch mounted on each side of said support, a casing for said switches having a front opening and a rear conduit outlet opening, the said support being mounted within the casing so that with the support in its normal position one of said switches faces the front opening of the casing and the second of said switches faces the rear conduit outlet opening of the casing, the second of said switches being accessible for inspection by tilting the said support toward the front opening.

5. A switch assembly comprising a casing

- having a rear conduit outlet opening, a terminal board mounted within the casing adjacent said opening, a switch panel pivotally mounted within said casing in front of said 5 opening, a contactor mounted on the front of said panel facing the front of the casing and a contactor mounted on the rear of the panel facing the said opening, the said contactor mounted on the rear of the panel being accessible by tilting the said panel about its pivot toward the front of the casing.
6. A switch assembly comprising a casing having a rear conduit outlet opening, a switch panel pivotally mounted within said casing in front of said opening, the pivotal mounting of the panel being arranged to permit ready removal of the panel from the casing, a contactor mounted on the front 15 of said panel facing the front of the casing and a contactor mounted on the rear of the panel facing the said opening, the said contactor mounted on the rear of the panel being accessible by tilting the said panel about its pivot toward the front of the casing, and a mechanical interlock extending through the said panel for preventing either of said contactors from closing while the other contactor is closed.
- 20 7. A switch assembly comprising a casing having a front opening and a rear conduit outlet opening, a supporting rod extending transversely of the casing, a switch panel having an open pivotal bearing on said rod so that the panel is supported by the rod and is readily removable from the casing, a contactor mounted on the front of said panel facing the front opening of the casing and a contactor mounted on the rear of said 25 panel facing the said conduit outlet opening of the casing, the said contactor on the rear of the panel being readily accessible by tilting the said panel toward the front of the casing.
8. A motor starting compensator comprising a casing having a conduit outlet opening at the upper rear end thereof, a terminal board mounted within the casing adjacent the said opening, a contactor panel pivotally mounted within said casing in front of 30 said opening, starting and running contactors mounted on said panel, the said contactors being mounted on opposite sides of said panel so that with the panel in normal position within the casing the contactor on the front of said panel is readily accessible from the front of the casing and the contactor on the rear of the panel is not readily accessible from the front of the casing, the said contactor on the rear of the panel being readily accessible from the front of the casing by swinging said panel about its pivotal support toward the front of the casing, an auto-transformer mounted within said casing beneath and to the rear of said panel, and a plurality of controlling relays mounted within said casing beneath and to the front of said panel independently of said panel and auto-transformer.
- 35 9. A motor starting compensator comprising a casing having a conduit outlet opening at the upper rear end thereof, a terminal board mounted within said casing on the rear wall thereof adjacent the said opening, an auto-transformer mounted on the rear wall of the casing below said terminal board, a supporting rod extending transversely of the casing intermediate the front and rear walls of the casing, a switch panel having an open pivotal bearing on said rod so that the panel is supported by the rod and is readily removable from the casing, starting and running contactors mounted on said panel, the said contactors being mounted on opposite sides of said panel so that when the panel is in normal position within the casing the contactor on the front of the panel is readily accessible from the front of the casing and the contactor on the rear of the panel is readily accessible from the front of the casing by swinging the panel about its pivotal support toward the front of the casing, a mechanical interlock extending through said panel for preventing either of said contactors from being closed while the other of said contactors is closed, and a plurality of controlling relays for said contactors mounted within said casing beneath and to the front of said panel.
- 40 10. In witness whereof, I have hereunto set my hand this 10th day of July, 1925.
- 45 GEORGE S. LEDDICK.
